UNITED STATES PATENT OFFICE.

ROBERT FRANZ WERK, OF NEW ORLEANS, LOUISIANA.

OIL-PRESS MAT.

SPECIFICATION forming part of Letters Patent No. 790,607, dated May 23, 1905.

Original application filed September 10, 1901, Serial No. 74,906. Divided and this application filed June 26, 1902, Serial No. 113,263.

To all whom it may concern:

Be it known that I, ROBERT FRANZ WERK, a citizen of the United States, and a resident of New Orleans, in the parish of Orleans and 5 State of Louisiana, have invented new and useful Improvements in Oil-Press Mats, of which the following is a full, clear, and exact description.

The present improvement in oil-press mats 10 is a division of an earlier application for Letters Patent filed September 10, 1901, Serial No. 74,906.

The improved mat is made of animal hair by weaving together threads or strands in a 15 well-known manner; and the distinguishing feature of the improvement resides in warp-threads made of soft hair. This overcomes the difficulty which is present more or less in all horsehair press-mats—namely, a liability 20 to unravel. The desired strength and durability of the mat is secured by the use of hard, stiff, and coarse hair in the production of the weft-threads.

Reference is to be had to the accompanying 25 drawings, forming a part of this specification, in which similar characters of reference indicate corresponding parts in both the figures.

Figure 1 is a plan view of an oil-press mat embodying the present invention, and Fig. 2 30 is a longitudinal sectional elevation, on the line 2 2 of Fig. 1.

As shown by the drawings, the mat or fabric consists of a plurality of longitudinal warp strands or threads A and a series of weft 35 threads or strands B, the latter extending transversely to the warp-strands. Before weaving the fabric it is first necessary to select and prepare the proper kinds of hair for the production of different strands or threads, 40 and in the present invention the warp-threads are made of soft pliable hair, while the weft-threads are composed of hard, stiff, and coarse hair. This combination of different kinds of hairs produces a mat or fabric which is entirely free from a tendency to unravel, and at 45 the same time the article possesses the desirable features of pliability, durability, and good drainage of the oil through the same.

The soft hair for the production of the

warp-threads is selected and arranged so as 50 to be spun or twisted together into a thread of the desired length and thickness. The weft threads or strands are made of hard, stiff, and coarse hair, which is properly selected and arranged so as to be spun and twisted 55 into thread of the desired length; but I prefer to make the weft threads or strands of increased thickness as compared with the thickness of the warp-strands.

The warp-strands are arranged in parallel 60 relation and in the same transverse plane, while the weft-threads are interwoven with the warp-strands in a manner to be entirely concealed and protected thereby. (See Fig. 2.) The warp-strands greatly exceed in number 65 per square inch the weft-threads, and in practice I prefer to use from five to eight times as many warp-strands as there are weft-threads in the fabric.

The arrangement of the warp-threads with 70 relation to the weft-threads secures a more uniform distribution of the pressure over the weft-threads.

By the above-described construction a very 75 strong and durable mat is produced. The weft-threads give to the mat great resisting power in a crosswise direction, thereby enabling the mat to resist the great lateral strain to which it is frequently subjected, and as the warp-threads have a tendency to spread and 80 flatten out they not only form a cushion for protecting the weft-threads, but they will not cut into the weft-threads and injure the same, as hard warps would do, and consequently 85 the life of the mat is prolonged.

Having thus described my invention, I claim 85 as new and desire to secure by Letters Patent—

1. An oil-press cloth or mat consisting of warp-threads and weft-threads each made of long animal hair, each warp-thread consisting 90 exclusively of soft pliable hair, and each weft-thread being made of hard, stiff and coarse hair; the soft, pliable warp-threads forming the selvage of the mat.

2. An oil-press mat consisting of warp- 95 threads and weft-threads each made of long animal hair; each warp-thread consisting exclusively of soft pliable hair, the warp-threads

at the middle of the mat being made of longer hair than the warp-threads at the selvage, and each weft-thread being made of hard, stiff and coarse hair; the number of warp-threads exceeding the weft-threads per inch, and the weft-threads being thicker than the warp-threads.

In testimony whereof I have signed my name to this specification in the presence of two subscribing witnesses.

ROBERT FRANZ WERK.
